UNITED STATES PATENT OFFICE.

GUSTAVE W. BERTHOLD, OF CHICAGO, ILLINOIS.

METERING PANEL BOARD.

Application filed October 30, 1922. Serial No. 597,905.

My invention relates to improvements in metering panel boards, and may be regarded particularly as effecting improvements in the panel board forming the subject of my copending application, Serial No. 140,144, filed January 2, 1917.

An object of my invention is to produce an improved metering panel board which requires a minimum amount of copper for a given number of circuits to be taken care of.

In office buildings and the like where the changing of tenants and rearrangement of offices is of frequent occurrence it is necessary that the connections on a metering panel board may be readily changed. Frequently it is desirable to connect a large number of load circuits across one meter, to accomplish which means should be provided for on the panel board. A further object therefore of my invention is to produce an improved panel-board of compact and simple construction which has all the functions commonly associated with boards of this character.

A further object of my invention is to produce a panel-board which is provided with gutters to permit of running jumper wires to the fuse terminals, and in which such gutters are positively closed to insure safety.

In the accompanying drawings, Figure 1 is a plan view of a meter paneling board, with certain parts broken away, which embodies the features of my invention. Fig. 2 is a sectional view taken along line 2-2 of Fig. 1, showing particularly the construction and relation of the inner and outer socket members for receiving fuse plugs of any desired construction. Fig. 3 is a perspective view of the block forming the base of the inner socket member. Fig. 4 is a bottom plan view of the inner socket member. Fig. 5 is a perspective view of the shell forming part of both inner and outer socket members. Fig. 6 is a perspective view of the conducting plate for the socket members. Fig. 7 is a perspective view of the plate which closes the gutters for receiving the various socket terminal connections.

The exemplary embodiment of my invention which is illustrated herein with considerable particularity comprises a base board

8 which may be of any suitable insulating material. The present embodiment is designed for a three wire system of distribution in which 9 and 10 represent the positive and negative terminals respectively, and 11 represents the common return or neutral terminal, but it should be understood that any other satisfactory or suitable system of distribution may be employed.

The positive and negative terminals are connected through fuses 12, capable of withstanding the total normal potential of that line, to the short bus-bars 13 and 14, respectively. Small fuses 15 of any suitable construction connect the various circuit terminals 16 to the short bus-bars. The neutral terminal 11 is electrically connected with the parallel bus bars 17 and 18 which are supported at opposite sides of the base board 8. A power switch 19 secured to the upper end of the board serves to connect the source of power to the bus-bars.

Mounted directly upon the long bus-bars 17 and 18 with their constituent elements in close abutment are two rows of socket members 20. Two parallel rows of socket members 21 are arranged between the socket members 20 so as to form a pair of side gutters 22 and 23, and a central gutter 24 of somewhat greater width. The corresponding socket members 20 and 21 are also aligned transversely of the bus-bars. The gutters which are designed to house the various lead wire connections to the socket members are provided with a plurality of holes 25 through which said lead wires enter. The holes 25 which are also arranged in transverse and longitudinal alignment are each intended for use with the adjacent socket members.

Referring to Fig. 2, the outer socket member 20 in the preferred form comprises a base 26 of insulating material which is provided with a notch 27 on its under side adapted to fit over the long bus bar 17. The block or base 26 is secured to the base board 8 by means of a bolt 28 which is surrounded by a sleeve 29 which fits into a countersunk bore 30 of the base. The bolt 28 extends through the board 8 into a countersunk bore in the rear of the base and is secured therein by means of a nut 31. The

bus bar 17 is secured to the socket member 20 by means of a screw bolt 32. The head of the screw bolt constitutes the central terminal of the socket. The other terminal 5 of the socket is in the form of a threaded annular sheet metal shell 33 which is held within the socket proper 34 into which the head of the screw bolt 32 projects.

In the particular construction shown here-
10 in, the shell 33 is held within the socket 34 by means of the bolt 32 forming the central terminal, and is insulated therefrom by an insulating washer 35. The lower end of the shell 33 has an inturned flange 36 which
15 fits against the bottom of the socket. A conducting member 37 extends into the shell 33 through a slot 38 and fits between the insulating washer 35 and the inside of the flange 36. The screw bolt 32 passes through
20 a metallic washer 39, the insulating washer 35, the conducting member 37, the shell 33, the block 26 and the bus bar 17, and acts to hold them all in rigid relation. The conducting member 37 is provided with a
25 large central aperture 40 whereby contact with the bolt 32 is prevented.

Said conducting member 37, one end of which extends into the side gutter 22 through an opening 41 on the inner side of the block
20 20, acts to connect the return lead wire of the load circuit to the shell terminal. This return lead from the load is secured to the conducting member by a fastening means 42 of any suitable form.

35 The inner socket member 21 in the present instance is of a construction similar to that of the outer socket member 20, except that the central terminal 32 of the socket is not connected to a bus bar but to a second con-
40 ducting plate 43 which extends into the gutter 22 through an opening 44 in the block. Fastening means 45 similar to those employed in the member 20 are used to secure the lead wire running to the load to the conducting
45 plate 43. The conducting member 37 of the inner socket member 21 acts to secure one lead of the meter circuit to the shell terminal 33 by a fastening means 46 which comprises a plate 47 bent to form a clamp. This form
50 of fastening means is here desirable so that a plurality of wires may be conveniently clamped to the same conducting member. The inner socket member 21 is of slightly
55 greater width than the outer socket member 20 and has a ledge on both sides to accommodate the two fastening means.

In the present instance the socket mem-
bers have rectangular bases and abut close together to form the side walls of the gutters.
60 Each socket member is made with two sockets for receiving fuse plugs of any standard construction. Although the socket members have been described with considerable par-
ticularity, members of any other suitable construction may be used if so desired.

The gutters are adapted to be closed by plates 48 of proper width and length, having downwardly bent end flanges 49 to close the ends of said gutters, and having side flanges 50. The socket members have notches 51 on their upper aligned edges bordering the gutters, into which the flanges 50 fit. The plates engage the upper ends of the spacer sleeves 29 and are held in place by the bolts 28 which pass through the spacers and the 75 blocks 26. If desired a series of numbers may be placed on the plates in positions overlying the corresponding holes 25 in the board 8.

Referring to Fig. 1, 52 represents an office 80 building or any other building structure where a plurality of separate load circuits are necessary. The load circuit wires, 53^a, 53^b, 53^c and 53^d which supply the loads 54^a, 54^b, 54^c and 54^d with power enter the side 85 gutters 22 and 23 through the holes 25 and are therein secured in pairs to the adjacent conducting plates 37 and 43. The meter circuit wires leading from the positive and neg-
90 ative terminals 9 and 10 through the various meters M, enter the central gutter 24 through holes 25 and are electrically connected to the various shell terminals of the inner socket members 21. The meters M may be connect-
95 ed in the customary manner by wires 55. 95

By the arrangement shown any load can be connected singly across a meter, or as in the case when one tenant may occupy a large number of rooms, a plurality of loads may be connected across one meter. The latter con-
100 nection is obtained by running jumper wires 56 between the wire securing means 46 to connect the shell contacts of the inner socket members 21. Thus, the loads 54^c and 54^d are connected to the same meter through the 105 meter circuit 57^c. The meters may be of the two wire or three wire type, the latter type being shown as receiving the meter circuit wires 57^c and 57^a.

It will be seen that by the construction 110 herein illustrated, the amount of copper which is ordinarily required for metering panel boards is greatly reduced. The board is simple in construction and cheap to produce. All connections on the board are completely covered by the gutter plates so that a "dead front" is obtained.

I desire to point out that while the invention has been herein illustrated and described with considerable particularity, I contem-
120 plate that various changes in form, construc-
tion and arrangement of parts may be made by those skilled in the art but without de-
parting from the spirit and scope of the in-
vention as expressed in the appended claims. 125

I claim as my invention:

1. A metering panel-board having in com-
bination, an insulating board, a pair of bus-
bars mounted thereon in parallel relation,
two rows of structurally separate fuse plug 130

- sockets mounted directly above the two bars with one terminal of each socket electrically connected to its bar, and two rows of structurally separate fuse plug sockets mounted on said insulating board parallel to and between said bus-bars one terminal of each of said last mentioned sockets being connected to a load circuit and the other terminal being connected to a meter circuit.
10. 2. A metering panel-board having, in combination, an insulating board, a pair of bus-bars mounted thereon in parallel relation, two rows of structurally separate fuse plug sockets mounted directly over the two bars, with one terminal of each socket electrically connected to its bar, two spaced rows of structurally separate fuse plug sockets mounted directly on said insulating board parallel to and between said bus-bars, the 15 rows of sockets providing three gutters for the wires leading to said sockets, and a plurality of plates for closing said gutters.
3. A metering panel-board having in combination, an insulating board, a positive and 20 a negative bus-bar mounted thereon, a neutral bus-bar having parallel branches mounted on said board, two rows of fuse plug sockets mounted directly over the two branches of said neutral bus-bar with one 25 terminal of each socket electrically connected to said bar and with the other terminal of each socket provided with a wire attaching device, two rows of fuse plug sockets forming a central gutter and mounted between said first mentioned rows, and cooperating 30 therewith to form the side walls of two side gutters, one terminal of each fuse plug socket in the two central rows having a wire attaching means in a side gutter and 35 the other terminal having a wire attaching means in the central gutter, said means in the central gutter connecting the meter circuit and said means in the side gutters connecting the load circuit to the board.
45. 4. A metering panel-board having in combination, an insulating board, two bus-bars of the same polarity mounted on said board, two outer rows of fuse plug sockets mounted directly over said bars with one terminal 40 of each electrically connected to its bar and the other terminal of each extending laterally from the inner side thereof, two inner rows of fuse plug sockets parallel to and between said first mentioned sockets, each 45 inner socket being paired with an opposed inner socket in the other inner row and with an opposed outer socket in the adjacent outer row, one of the terminals of each inner socket facing the laterally extending terminal of said opposed outer socket and being 50 attached therewith to wires leading to the load circuits, and the other of the terminals of each inner socket facing the corresponding terminal of said opposed inner socket, and being attached therewith to wires leading to the meter circuits.
5. A metering panel-board having in combination an insulating board, a bus-bar mounted thereon, a row of closely abutting fuse plug sockets mounted on said bar, one terminal of each being electrically connected with said bar, a second row of fuse plug sockets parallel to said first mentioned row, with one terminal of each socket and one terminal of each of said first mentioned 75 sockets being attached to wires leading to a load circuit, and means for electrically connecting a plurality of the terminals of said last mentioned sockets, said means being connected to a meter circuit whereby a plurality 80 of loads can be connected to one meter to register their combined power consumption.
6. A metering panel board having, in combination, an insulating board, positive and negative bus bars mounted on said board, a neutral bus bar of forked construction mounted on said board, two rows of fuse plug sockets mounted over the branches of said neutral bus bar with one terminal of each socket electrically connected thereto, 90 two rows of fuse plug sockets mounted on said board independent of bus bars between said first mentioned rows and cooperating therewith to form two side gutters and a central gutter, each of said sockets being provided with a terminal connection extending into a side gutter for attaching a load circuit, and each socket of said last two rows being provided also with a terminal connection extending into said central gutter for 95 attaching a meter circuit, and means for connecting a plurality of said last mentioned terminal connections to connect a plurality of load circuits through one meter.
7. A metering panel board having, in combination, an insulating board, positive and negative bus bars mounted on said board, a neutral bus bar having parallel branches mounted on said board, load and meter circuits, two rows of fuse plug sockets mounted directly on the branches of said neutral bus bar, with one terminal of each socket electrically connected thereto, and two spaced rows of fuse plug sockets mounted on said board between said first mentioned rows and 110 cooperating therewith to define two side gutters and a central gutter, each socket being provided with a terminal connection extending into a side gutter, and each socket of the two last mentioned rows being provided also 115 with a terminal connection extending into the central gutter, the terminal connections in the side gutters being connected to one set of circuits and those in the central gutter being connected to the other set of circuits.
8. A metering panel board having, in combination, an insulating board, a bus bar mounted on said board, a row of fuse plug

sockets mounted directly over said bus bar, each socket having one terminal electrically connected to said bar, a row of fuse plug sockets mounted on said board independent of a bus bar and parallel to said first mentioned row to form a gutter with the latter, each socket having a terminal connection extending into said gutter and each socket of said last mentioned row having also a ter-

10 minal connection extending laterally at its outside, the terminal connections within said gutter being adapted to connect a load circuit and the outside terminal being adapted to connect a meter circuit.

In testimony whereof, I have hereunto affixed my signature.

GUSTAVE W. BERTHOLD.
